UNITED STATES PATENT OFFICE

137,025

DESIGN FOR A PRESSING DEVICE

John J. Getgey, Cincinnati, Ohio, assignor to
Empire Products, Inc., Cincinnati, Ohio, a cor-
poration of Ohio

Application June 24, 1943, Serial No. 110,517

Term of patent 14 years

To all whom it may concern:

Be it known that I, John J. Getgey, a citizen
of the United States, residing at Cincinnati, in
the county of Hamilton and State of Ohio, have
invented a new, original, and ornamental Design
for Pressing Device, of which the following is
a specification, reference being had to the ac-
companying drawing, forming a part thereof.

Figure 1 is a side elevational view of a press-
ing device embodying my new design;

Figure 2 is an elevational view of the other side
thereof;

Figure 3 is an end elevational view; and

Figure 4 is a sectional view thereof taken on
line 4—4 of Figure 2.

I claim:

The ornamental design for a pressing device,
substantially as shown.

JOHN J. GETGEY.
